(57) **CLAIM**

The ornamental bed frame foot bumper, as shown and described.

DESCRIPTION

FIG. 1 is an isometric view of the present design, defining top, bottom, left and right sides for drawings 2-5.

FIG. 2 is a right view of the present design.

FIG. 3 is a left view of the present design.

FIG. 4 is a top view of the present design.

FIG. 5 is a bottom view of the present design.

FIG. 6 is a reduced scale, isometric view of the present design showing installation on a typical bed frame; and,

FIG. 7 is an isometric, cross sectional view taken along lines 7-7 of FIG. 4.

The broken line showing of a partial bed frame is included for the purpose of illustrating environmental structure and forms no part of the claimed design.
